UNITED STATES PATENT OFFICE.

JOHN A. WRIGHT, OF IRWIN, AND WILLIAM F. O'NEILL, OF WILKINSBURG, PENNSYLVANIA.

KNIFE-SWITCH.

SPECIFICATION forming part of Letters Patent No. 695,188, dated March 11, 1902.

Application filed July 12, 1901. Serial No. 68,015. (No model.)

To all whom it may concern:

Be it known that we, JOHN A. WRIGHT, residing at Irwin, in the county of Westmoreland, and WILLIAM F. O'NEILL, residing at 5 Wilkinsburg, in the county of Allegheny, State of Pennsylvania, citizens of the United States, have invented certain new and useful Improvements in Knife-Switches, of which the following is a specification, reference being 10 had therein to the accompanying drawings.

This invention relates to knife-switches, and more particularly to improvements on the switch patented to John A. Wright December 4, 1900, No. 663,209.

15 The primary object is to provide a double blade of simple and improved construction and also to provide improved means for securing the blade to the handle or handle cross-bar, whereby said parts are rigidly 20 united and the rigidity maintained without danger of loosening.

25 The invention consists in the novel features of construction and in the combination and arrangement of parts hereinafter fully described and claimed, and illustrated by the accompanying drawings, wherein—

Figure 1 is a plan view, and Fig. 2 a side elevation, of a switch constructed in accordance with our invention, both views being 30 partly in section. Fig. 3 is a plan view, partly in section, of a single-blade switch provided with our improvement. Fig. 4 is a detail view of one of the blade members. Fig. 5 is an end elevation of a two-blade handle-bar 35 shown partly in section.

Referring to the drawings, 2 represents the base, and 3 the contact-posts, the latter being preferably of the form shown in the patent to John A. Wright, before referred to. Each of 40 the switch-blades is double, being formed of two parallel members 4, hinged to one of contacts 3 at 5 in the usual manner. The swinging ends of the blade members are bulged oppositely at 6, and the extremities 7 thereof are 45 brought flatly together, being outwardly disposed in line with the longitudinal center of the double blade. In the two-blade switch shown in Figs. 1 and 2 the blade extremities

7 enter a vertical notch 8', formed in the inner face of cross-bar 8, to which handle 9 is 50 secured. In the single-blade switch of Fig. 3 the handle 10 is notched to receive said projections. In both constructions the blade extremities 7 are longitudinally apertured or notched at 11, so that when the blade members are placed together these apertures or notches form a way for securing screw 12, and the bulges 6 provide space for the securing-nut 12'. Said bulges also add resilience to the blade members and cause the latter and 60 the contacts to coöperate in a most effective manner. With the blade and handle elements thus interlocked it is practically impossible for the same to work loose or for the handle or handle cross-bar to turn on the 65 blades. Even if the securing-nuts 12' should slacken or become loose said parts could not work loosely one upon the other. The blade members thus constructed are very simple of manufacture and may be readily assembled 70 and at the same time are thoroughly interchangeable.

Having thus fully described our invention, what we claim as new, and desire to secure by Letters Patent, is—

75

1. The combination of a double switch-blade bulged in opposite directions at its handle end, said double blade having a projecting part outside of the bulge, and a handle member notched to receive said projection, 80 substantially as shown and described.

2. The combination of a double switch-blade oppositely bulged at its handle end and formed with a central longitudinal projecting portion outside of the bulge, said projecting 85 portion being longitudinally apertured, a handle member formed with a notch to receive the blade projection, and a securing-screw extending through the aperture of the blade projection and uniting the blade and handle member, substantially as shown and described.

3. The combination of a double switch-blade formed of two longitudinal members, said members being oppositely bulged at their handle ends and having short extremities 90 flatly engaging each other and projecting lon- 95

itudinally from the blade bulges, said extremities being longitudinally apertured, a handle member notched to receive the said projecting blade extremities, and a screw extending through said aperture and securing together the blade and handle member, substantially as shown and described.

In testimony whereof we affix our signatures in presence of two witnesses.

JOHN A. WRIGHT.
WM. F. O'NEILL.
